(57) CLAIM

(21) Appl. No.: **29/325,968**

The ornamental design for a tire sidewall, as shown and described.

(22) Filed: **Oct. 9, 2008**

DESCRIPTION

(51) LOC (9) Cl. **12-15**

FIG. 1 is a front elevational view of a tire sidewall showing my new design; and,

(52) U.S. Cl. **D12/605**

FIG. 2 is a front elevational view of a second embodiment thereof showing the disclaimed portions of FIG. 1 in solid lines.

(58) Field of Classification Search D12/500-501,
D12/503, 600, 604-605; 152/DIG. 12, 523-524,
152/555; D7/396.4-396.5, 588

In the drawings, the broken lines showing of the tire tread, inner bead and the peripheral boundary between the tire tread and the sidewall in FIG. 1 depict environmental subject matter and form no part of the claim.

See application file for complete search history.
